MAXIMUM VALUE DETERMINING DEVICE

Wilhelm Bilz, Schwaig-Nuremberg, Germany, assignor to Siemens-Schuckertwerke Aktiengesellschaft, Erlangen, Germany, a corporation of Germany

Application March 12, 1957, Serial No. 645,617

Claims priority, application Germany March 17, 1956

9 Claims. (Cl. 235—145)

This invention relates to a device for determining the maximum number value of a series of numbers and has particular relation to such a device including relays energizable in response to actuation of a plurality of sets of keys corresponding to different digit places of a number.

According to the invention a device of improved construction is provided for determining the maximum number value of a series of numbers. The device includes keying means comprising a number of control relays which are energizable in response to actuation of a plurality of sets of keys. The sets of keys correspond to different digit places of a number. For example, one set of keys may correspond to the hundreds digit of a number. Another set of keys may correspond to the tens digit of a number and a final set of keys may correspond to the units digit of a number. The keys of each set may represent different digits between zero and nine.

The control relays are arranged for energization from a suitable voltage source in response to actuation of the keys to effect a number of control functions. Voltage from the voltage source is applied to the control relays by a voltage applicator which is effective to successively place the control relays under voltage in the digit place sequence starting at the highest digit place. The arrangement is such that the voltage applicator is effective to place the control relays under voltage in the proper sequence only if a digit ready for keying in the set corresponding to the highest digit place is equal to or larger than a digit previously keyed into such set.

The control functions exerted by the control relays include the establishment of a holding circuit for an energized control relay when a digit to be keyed into a set is equal to or greater than a digit previously keyed into such set. Such a holding circuit maintains energization of the control relay to effect the keying of a digit. The control relays are also effective when energized to prevent the subsequent keying of a digit in a set which is smaller than a digit previously keyed into such set.

Suitable erasing means is provided for erasing digits of a previously keyed number when a digit to be keyed into the set corresponding to the highest digit place is larger than the previously keyed digit. For this purpose erasing relays are provided for energization in response to the keying of a digit in a digit set which is larger than a digit previously keyed into such set. When so energized, the erasing relays effect interruption of the holding circuit of an energized control relay in the next lower digit set to thereby deenergize the control relay to permit the subsequent keying of digits in such lower set.

Suitable registering means is provided to effect the registering or recording of a number in response to keying of the number. Preferably, such registering means is connected for operation through the voltage applicator when voltage is applied to the units digit set.

It is, therefore, an object of the invention to provide

2

a device of improved construction for determining the maximum number value of a series of numbers.

It is another object to provide a device as defined in the preceding paragraph including a number of relays energizable in response to actuation of a plurality of sets of keys corresponding to different digit places of a number with the keys of each set representing a different digit.

It is still another object of the invention to provide a device as defined in the preceding paragraphs including control relays effective when energized to prevent the effective keying of a digit in a set which is smaller than a digit previously keyed into such set.

It is a still further object of the invention to provide a device for determining the maximum number value of a series of numbers including control relays effective when energized to key digits of a number in key sets corresponding to different digit places of the number with erasing means effective in response to the keying of a digit in the set corresponding to the highest digit place which is larger than the digit previously keyed in such set for deenergizing control relays in the lower digit place sets.

Other objects of the invention will become apparent from the following description taken in conjunction with the accompanying drawing in which the single figure illustrates a maximum value determining device constructed in accordance with the teachings of the present invention.

Referring to the drawing, the single figure illustrates a device for determining the maximum number value of a series of numbers. The device illustrated is capable of investigating numbers having a maximum value of 999. It is to be understood, however, that devices may be constructed according to the invention which are capable of investigating a number having other maximum values such as 9,999.

The device illustrated includes voltage applicator means shown as enclosed in the broken line rectangle 12 for applying voltage to keying means illustrated as enclosed in the broken line rectangle 14. The voltage applicator 12 includes a manually actuatable starting switch S1 which is effective when in a closed condition to prepare a first applicator relay having an operating winding A for energization in response to actuation of a hundreds key from a source of voltage which is represented by a battery 16. The winding A is effective when energized to operate a pair of normally open switches a1 and a2 to closed positions.

Closing of the switch a2 serves to prepare a second applicator relay including an operating winding B for energization in response to actuation of a tens key from the source 16 through the closed switches S1 and a2. Closure of the switch a2 also permits the application of voltage from the source 16 to control relays of the tens digit set of the keying means 14 in response to actuation of a tens key as will presently appear.

Energization of the winding B effects operation of a pair of normally open switches b1 and b2 to closed positions to thereby prepare a winding C of a third applicator relay for energization in response to actuation of a units key from the source 16 through the closed switches S1, a2 and b2. Closure of the switch b2 also permits the application of voltage from the source 16 to control relays of the units digit set of the keying means 14 in response to actuation of a units key. Energization of the winding C is effective to operate a pair of normally open switches c1 and c2 to closed positions. When the switch c2 is closed, an operating winding D of a registering relay is energized to operate a suitable registering device (not shown) for the

purpose of registering or marking the value of a number keyed into the keying means 14.

It will be recalled that energization of the windings A, B, C effects operation respectively of normally open switches *a*1, *b*1 and *c*1 to closed positions. Closure of these switches operates to connect the associated applicator relay windings for energization from the source 16 through the closed switch S1 and a conductor M. This arrangement operates to maintain energization of the applicator relay windings A, B and C when the actuatable keys of the keying device 14 are released subsequent to actuation thereof. Suitable resistors VA, VB and VC are connected in series respectively with windings A, B and C to limit current flow through the associated windings.

The keying means 14 includes a plurality of sets of actuatable keys which represent respectively the hundreds digit, the tens digit and the units digit of a number. The keys of each set represent different digits between zero and nine. In the single figure the keys of the hundreds set are represented by the reference characters T000, T100, T200, T300, T400, T500, T600, T700, T800 and T900. The keys of the tens set are represented respectively by the reference characters T00, T10, T20, T30, T40, T50, T60, T70, T80 and T90. In a similar manner the keys of the units set are represented respectively by the reference characters T0, T1, T2, T3, T4, T5, T6, T7, T8 and T9.

A suitable control relay is associated with each of the actuatable keys. For example, a control relay having an operating winding 100 is associated with the key T100 in the hundreds set. Each of these control relays includes a plurality of switches operable in response to energization of its operating winding to effect a number of control functions. As an example, energization of the winding 100 of the control relay for the key T100 in the hundreds set is effective to operate five switches 100-1, 100-2, 100-3, 100-4 and 100-5. The effect of these switches will be described hereinafter. The control relays for the tens and units sets are similar except that the control relays for the units set excepting the zero digit relay include but two switches instead of five switches as is the case for the control relays of the hundreds and tens sets with the exception of the zero and nine digits in these sets.

Each applicator relay winding is included in a separate conductor through which it is initially energized in response to actuation of a key in the associated key set. For example, the winding A of the first applicator relay of the voltage applicator 12 is connected in a conductor H100 to which is connected a key contact of each key in the hundreds set. In a similar manner windings B and C of the following applicator relays are included in conductors H10 and H1. Key contacts of keys in the tens and units set are connected to these conductors.

A separate self-holding conductor for the control relay windings of each key set is connected to the positive terminal of the source 16 through a conductor N1. For example, the conductor G100 forms part of a holding circuit for the windings of the control relays of the hundreds set. In a similar manner self-holding conductors G10 and G1 are provided for the control relay windings in the tens and units sets. The conductors G100, G10 and G1 comprise portions of paths through which energization of the respective control relay windings is maintained subsequent to the release of an actuated key.

As will presently appear, energization of an operating winding is effected subsequent to energization of an associated erasing relay through conductors K100 and K10 included respectively in the hundreds and tens sets. The control relay windings are connected to these conductors

in response to energization of the erasing relay windings through conductors J100 and J10.

Each of the control relays includes switches which are effective when operated in response to energization of the associated operating winding to change the path of energization of the associated operating winding. For example, the control relay for the key T100 includes a normally open self-holding switch 100-1 having a terminal connected to the conductor G100. Closure of the switch 100-1 is effective to connect the winding 100 to the conductor G100 for maintaining energization of the winding 100 subsequent to release of the actuated key T100. Similar self-holding switches are provided for the control relays in the tens and units sets.

15 The control relays for the hundreds and tens sets each includes a normally open switch for connecting the operating windings to the conductors K100 and K10. For example, the relay for the key T100 includes a switch 100-2 having one terminal connected to the conductor J100 through which the winding 100 is initially energized and having a second terminal connected to conductor K100 through which the winding 100 is energized subsequent to closure of the switch 100-2. A similar switch is included in each of the control relays for the tens set. 20 However, such a switch is not employed in the control relays for the units set.

Each of the control relays for the hundreds and tens set also includes a normally closed switch for interrupting the conductor through which the associated operating winding is initially energized. This switch for the control relay of the key T100 is represented by the reference numeral 100-3 and is included in the conductor J100. The control relays for the tens set include similar switches represented by the numerals 10-3, 20-3, 30-3, etc. which are included in the conductor J10 forming a part of the circuit through which the associated operating windings are initially energized.

Each of the control relays for the hundreds and tens sets with the exception of the relays for the zero keys in such sets includes a pair of normally closed switches operable to open positions when the associated operating winding is energized to prevent subsequent keying of a digit in a set which is smaller than a digit previously keyed in such set. For example, the control relay for the key T100 includes switches 100-4 and 100-5 connected respectively in the conductors J100 and K100. When the winding 100 is energized, the switches 100-4 and 100-5 are opened to interrupt the paths which include the conductors J100 and K100 to thereby prevent energization of the winding 000 in response to actuation of the key T000. The control relays in the units set each includes a single switch for this purpose. These switches are represented by the reference characters 1-2, 2-2, etc. and are included in the conductor K1.

55 In order to erase a digit previously keyed into a digit set when a digit to be subsequently keyed in such set is equal to or larger than the previously keyed digit, suitable erasing means is provided. As illustrated in the single figure, the erasing means is enclosed in the broken line rectangle 18. Such erasing means includes a pair of relays connected for energization in response to actuation of keys in the hundreds and tens sets. These erasing relays include respectively operating windings E and F each effective when energized to operate a plurality of switches.

For example, the winding E operates when energized a plurality of switches *e*1, *e*2, *e*3 and *e*4. In a similar manner, the winding F operates switches *f*1, *f*2, *f*3 and *f*4. The normally open switches *e*1 and *f*1 are effective when operated to closed positions to establish holding circuits for the associated windings E and F to maintain energization of these windings through conductors H100 and H10 when actuated keys in the hundreds and tens sets are released.

The normally closed switches *e2* and *f2* of the erasing relays are included respectively in the conductors *J100* and *J10* to interrupt these conductors when operated to opened positions. The erasing relays also include normally open switches *e3* and *f3* effective when operated to connect the control relay windings for the hundreds and tens sets to conductors *K100* and *K10* respectively. The switches *e2*, *e3* and *f2*, *f3* cooperate to remove the windings *E* and *F* from the paths of energization of the control relay windings to increase current through the control relay windings. This increased current is sufficient to effectively energize the control relay windings.

The erasing relays include finally switches *e4* and *f4* which effect the erasing function. For this purpose, the switches *e4* and *f4* are included in a conductor *Q* which forms a portion of the holding circuits for the operating windings of the control relays in the tens and units sets. These switches are effective when operated in response to energization of the windings *E* and *F* to interrupt the conductor *Q* to thereby deenergize control relays of the tens and units sets for effecting the erasing function. A pair of manually operable switches *S2* and *S3* are included in the energizing circuits for the windings *E* and *F* to effect deenergization of these windings for permitting subsequent keying of digits in the tens and units sets. It is noted that no erasing relay is provided for the units set.

The applicator, control and erasing relays are designed so that the switches of these relays in a given digit set operate in a preselected sequence in response to actuation of a key in such set. The arrangement is such that applicator relay switches are the first to operate followed by erasing relay switches and finally control relay switches.

Operation of the device will now be described. All of the relay switches and manually operated switches are initially in the positions illustrated in the single figure. Let it be assumed that it is desired to key the number 444 into the device.

The switch *S1* is initially closed and the key *T400* is actuated to bridge its associated key contacts. When this key is actuated, current will flow from the positive terminal of the source *16* through the closed switch *S1*, the winding *A*, the key *T400*, the winding *400*, the switch *400-3*, conductor *J100*, switch *e2*, winding *E*, the switch *S2* and back to the negative terminal of the source *16* through a switch *S4*. Such current flow is effective to initially energize the winding *A* to operate the associated switches to positions other than those shown in the single figure. Switch *a1* is closed to maintain energization of the winding *A* through the conductor *M* and the switch *S1*. Switch *a2* is also closed to prepare the winding *B* for energization in response to actuation of a key in the tens set.

Prior to operation of the control relay switches the winding *E* is energized to operate its switches. The switch *e1* is thereby operated to a closed position to establish a holding circuit for the winding *E* to maintain energization of this winding through the conductor *H100* independently of the conductor *J100*. At the same time switch *e2* is opened to disconnect the winding *E* from the conductor *J100*. Closing of the switch *e3* is effective to connect the winding *400* to the conductor *K100* through the conductor *J100*. The erasing switch *e4* is opened to interrupt the conductor *Q* but without any effect at this stage. Since winding *E* is now removed from the path of energization of winding *400*, current through winding *400* is now sufficient to cause operation of switches associated with winding *400*.

Energization of the winding *400* operates to close the switch *400-1* to maintain energization of the winding *400* when the key *T400* is released through a portion of the conductor *G100*. At the same time, switch *400-2* is closed to connect the winding *400* to the conductor *K100*.

At the same time switch *400-3* is opened to interrupt that portion of conductor *J100* which is associated with the digits of the hundreds set larger than the digit 4. The switches *400-4* and *400-5* are also at this time opened to interrupt respectively portions of the conductors *J100* and *K100* which are associated with control relay windings for digits smaller than the digit 4 in the hundreds set.

It is observed now that energization of the winding *400* is maintained from the source *16* through the conductor *N1*, conductor *G100*, switch *400-1*, switch *400-2* and that part of conductor *K100* which extends beneath switch *400-5*. It is also noted that energization of the winding *E* is maintained through the conductor *H100* independently of the winding *400* to thereby permit sufficient current flow through the winding *400* to maintain its energization. At this stage the digit 4 is effectively keyed into the hundreds set. The next action involves the manual opening of the switch *S2* for the purpose of deenergizing the winding *E*. This results in a return of the switches associated with the winding *E* to the positions shown in the single figure.

In order to key the digit 4 of the number 444 into the tens set, the key *T40* is actuated to bridge the associated key contacts. This results in current flow from the positive terminal of the source *16* through closed switches *S1* and *a2*, winding *B*, conductor *H10*, key *T40*, winding *40*, closed switch *40-3*, conductor *J10*, closed switch *f2* of the erasing relay, winding *F*, closed switch *S3* and back to the negative terminal of the source *16* through closed switch *S4*. The same action which occurred in the keying of the hundreds digit 4 now results in the keying of the tens digit 4.

Energization of the winding *40* is maintained through closed switch *e4*, conductor *G10*, closed switches *40-1* and *40-2* and conductor *K10*. Switches *40-4* and *40-5* are opened to interrupt respectively portions of conductors *J10* and *K10* for preventing subsequent energization of control relay windings for digits in the tens set smaller than the digit 4. Energization of winding *F* of the erasing relay is maintained through conductor *H10* and closed switch *f1*. At this time the digit 4 is effectively keyed into the tens set. The next step involves the manual opening of switch *S3* to effect deenergization of winding *F*.

In order to key the units digit 4 of the number 444 into the units set, the key *T4* is actuated with the result that winding 4 is energized to close switch *4-1* and to open switch *4-2*. Closure of switch *4-1* maintains energization of winding 4 through conductor *G1* and closed erasing switches *e4* and *f4* when key *T4* is released. Opening of switch *4-2* effectively interrupts that part of conductor *K1* which connects the control relay windings of digits in the units set which are smaller than the digit 4 whereby a previously keyed lower units digit is erased.

Winding *C* of the third voltage applicator relay is also energized to close its switches *c1* and *c2*. Closure of *c1* maintains energization of winding *C* when key *T4* is released from its actuated position. Closure of switch *c2* effectively connects a winding *D* for energization from the source *16* through closed switches *S1*, *a2*, *b2* and *S4*. Energization of winding *D* is effective to operate a suitable registering device (not shown) which records the keyed number 444 in any suitable manner.

The next step involves manual operation of the switch *S1* to open this switch. This action interrupts the holding circuit for the windings *A*, *B* and *C* of the voltage applicator relays whereby the switches associated with these windings return to the positions shown in the drawing. The number 444 is, however, still keyed into the keying means 14 inasmuch as the holding circuits for the control relays representing digits of this number are independent of the switch *S1*. It is further noted at this stage that control relays representing digits in the respective sets which are smaller than the digit 4 cannot be en-

ergized by actuation of keys for such control windings. This is for the reason that the switches 400-4, 40-4 and 4-2 are in their open positions to prevent such energization. However, control relays associated with keys representing digits equal to or greater than the digit 4 may be energized through the respective conductors J100, J10 and K1 in response to actuation of keys for such control relays.

As a result, a number having a value less than 444 cannot be keyed into the device. If, for example, the number 387 is to be keyed in, the temporary actuation of key 300 causes no effect inasmuch as the circuit including the conductor J100 is interrupted by the open switch 400-4. Consequently, windings A and E remain deenergized with the result that an erasing function by the switch e4 cannot take place. Furthermore, the winding B in the voltage applicator cannot be prepared for energization since the switch a2 remains open. Consequently, actuation of the keys T80 and T7 in the tens and units sets is ineffective to energize the relays associated with such sets.

Let it be assumed now that the number 444 is to be keyed in again. S1 is initially closed. Actuation of the keys T400, T40 and T4 effects energization of windings A, B and C through conductors H100, H10 and H1 and conductors K100, K10 and K1. However, since conductors J100 and J10 are interrupted such key actuation is ineffective to cause energization of windings E and F. Consequently, no erasing action takes place but the number 444 will again be registered inasmuch as the winding D will be energized through the closed switches a2, b2 and c2.

Let it be assumed now that the number 445 which is larger than the number 444 is to be keyed in. For this condition, the device will operate as explained in connection with the number 444 up until the time the units digit 5 is to be keyed. When the key T5 is actuated to key the units digit 5, the winding C of the voltage applicator is energized through closed switches S1, a2, b2, conductor H1, key T5, winding 5, and the closed switches 6-2, 7-2, 8-2 and 9-2 included in conductor K1. Energization of winding C causes closure of switches c1 and c2 with switch c1 maintaining energization of winding C. When winding 5 is energized, switch 5-1 is closed to maintain energization of winding 5 through conductor G1 and closed switches e4 and f4. Simultaneously, switch 5-2 is opened to thereby interrupt the holding circuit of winding 4 corresponding to previously keyed units digit 4. When switch c2 is closed, winding D is energized to thereby operate the registering device (not shown) to register the new number 445. After the number 445 is keyed and registered, the switch S1 may be opened to deenergize the windings of the voltage applicator relays.

As a final example, let it be assumed that the number 544 is to be keyed. The switch S1 is initially closed. The key T500 is actuated resulting in initial effective energization of the winding A followed in order by effective energization of the winding E of the erasing device and the winding 500. Effective energization of winding E results through conductor H100, key T500 and conductor J100. This is effective to open switch e4 to thereby erase previously keyed digits 4 and 5 respectively in the tens and units sets by interrupting the holding circuits for the associated control relay windings.

Winding 500 is then effectively energized and is held in the energized condition by closed switch 500-1. Closed switch 500-2 transfers winding 500 from conductor J100 to conductor K100. Switch 500-5 is now open to thereby interrupt the holding circuit for winding 400 corresponding to previously keyed hundreds digit 4. Switch S2 may now be opened to deenergize winding E to thereby return switch e4 to its illustrated position. The tens and units digits 4 of the number 544 may then be keyed

in the same manner as explained in connection with keying of the number 444.

The keys may be actuated in any suitable manner. If desired, the keys may be actuated either manually or automatically in response to the passage of a punched tape relative to the keys which may effect actuation of the keys in any suitable manner according to the numbers represented by the tape punchings.

Although the invention has been described with reference to certain specific embodiments thereof, numerous modifications are possible and it is intended to cover all modifications falling within the spirit and scope of the invention.

I claim as my invention:

1. In a device for determining the maximum number value of a series of numbers, a plurality of sets of actuatable keys with the sets corresponding to different digit places of a number, the keys of each set representing different digits between zero and nine, a source of voltage, a separate control relay for each of said keys, each of said control relays being energizable from said source in response to actuation of its key, control means including first means operable in response to energization of a control relay to maintain energization of such control relay when its key is released to key in the represented digit, said control means also including second means operable to prevent energization of control relays in response to subsequent actuation of keys in a set corresponding to digits smaller than a digit previously keyed in such set, erasing means energizable from said source in response to actuation of a key in a set representing a digit larger than a previously keyed digit in such set for deenergizing an energized control relay in the next following set, and a registering relay winding energizable in response to each keying of a number for effecting registration of said keyed number.

2. In a device for determining the maximum number value of a series of numbers, a plurality of sets of actuatable keys with the sets corresponding to different digit places of a number, the keys of each set representing different digits between zero and nine, a source of voltage, a start switch, voltage applicator means for applying voltage from said source to said keys, said start switch being effective when closed to prepare said applicator means for energization from said source, said applicator means being energizable from said source through said closed start switch in response to actuation of a key in the key set corresponding to the highest digit place for permitting the application of voltage to keys in the next following set in response to actuation of a key in the following set, a separate control relay for each of said keys, each of said control relays being energizable from said source in response to actuation of its key, control means including first means operable to maintain

energization of a control relay when its key is released to key in the represented digit, said control means also including second means operable to prevent energization of said applicator means and control relays in response to subsequent actuation of keys in a set corresponding to digits smaller than a digit previously keyed in such set, erasing means energizable from said source in response to actuation of a key in a set representing a digit larger than a previously keyed digit in such set for deenergizing an energized control relay in the next following set, and a registering relay winding energizable in response to each keying of a number for effecting registration of said keyed number.

3. In a device for determining the maximum number value of a series of numbers, a plurality of sets of actuatable keys with the sets corresponding respectively to hundreds, tens and units digits, the keys of each set representing different digits between zero and nine, a source of voltage, a separate control relay for each of said keys, each of said control relays being energizable from said source in response to actuation of its key to operate a

4. In a device for determining the maximum number value of a series of numbers, a plurality of sets of actuatable keys with the sets corresponding to different digit places of a number, the keys of each set representing different digits between zero and nine, a source of voltage, a start switch, voltage applicator means for applying voltage from said source to said keys, said start switch being effective when closed to prepare said applicator means for energization from said source, said applicator means being energizable from said source through said closed start switch in response to actuation of a key in the key set corresponding to the highest digit place for permitting the application of voltage to keys in the next following set in response to actuation of a key in the following set, a separate control relay for each of said keys, each of said control relays being energizable from said source in response to actuation of its key, control means including first means operable to maintain

energization of a control relay when its key is released to key in the represented digit, said control means also including second means operable to prevent energization of said applicator means and control relays in response to subsequent actuation of keys in a set corresponding to digits smaller than a digit previously keyed in such set, erasing means energizable from said source in response to actuation of a key in a set representing a digit larger than a previously keyed digit in such set for deenergizing an energized control relay in the next following set, and a registering relay winding energizable in response to each keying of a number for effecting registration of said keyed number.

plurality of control switches, a first control switch of each control relay being effective when operated to maintain energization of its control relay when its actuated key is released to key in the represented digit, a second control switch of each control relay being effective when operated to prevent energization of control relays in response to subsequent actuation of keys in a set corresponding to digits smaller than a digit previously keyed in such set, a tens digit erasing relay energizable from said source in response to actuation of a hundreds key representing a hundreds digit larger than a previously keyed hundreds digit for operating a first erasing switch, said first erasing switch being effective when operated to deenergize the control relay corresponding to a previously keyed tens digit, a units digit erasing relay energizable from said source in response to actuation of a tens key representing a tens digit larger than a previously keyed tens digit for operating a second erasing switch, said second erasing switch being effective when operated to deenergize the control relay corresponding to a previously keyed units digit, and a registering relay winding energizable in response to each keying of a number for effecting registration of said keyed number.

4. In a device for determining the maximum number value of a series of numbers, a plurality of sets of actuatable keys with the sets corresponding respectively to hundreds, tens and units digits, the keys of each set representing different digits between zero and nine, a source of voltage, a start switch, a plurality of voltage applicator relays for applying voltage from said source to said keys, said start switch being effective when closed to prepare a first applicator relay for energization from said source, said first applicator relay being energizable from said source through said closed start switch in response to actuation of a hundreds key to operate a first applicator switch, said first applicator switch being effective when operated to prepare a second applicator relay for energization from said source through said closed start switch, the second applicator relay being energizable through said operated first applicator switch in response to actuation of a tens key to operate a second applicator switch, said second applicator switch being effective when operated to prepare a third applicator relay for energization from said source through said closed start switch, the third applicator relay being energizable through said operated first and second applicator switches in response to actuation of a units key to operate a third applicator switch, a separate control relay for each of said keys, each of said control relays being energizable from said source through said closed start switch and the associated applicator relay in response to actuation of its key to operate a plurality of control switches, a first control switch of each control relay being effective when operated to maintain energization of its control relay independent of said start switch when its actuated key is released to key in the represented digit, a second control switch of each control relay being effective when operated to prevent energization of associated applicator relays and control relays in response to subsequent actuation of keys in each set corresponding to digits smaller than digits previously keyed in each set, a tens digit erasing relay energizable from said source in response to actuation of a hundreds key representing a hundreds digit larger than a previously keyed hundreds digit for operating a first erasing switch, said first erasing switch being effective when operated to deenergize the control relay corresponding to a previously keyed tens digit, a units digit erasing relay energizable from said source in response to actuation of a tens key representing a tens digit larger than a previously keyed tens digit for operating a second erasing switch, said second erasing switch being effective when operated to deenergize the control relay corresponding to a previously keyed units digit, and a registering relay winding energizable in response to operation

of said third applicator switch for effecting registration of the number resulting from successive keying of digits in said hundreds, tens and units sets, said start switch being effective when opened to deenergize said applicator relays for permitting a subsequent keying operation.

5. In a device for determining the maximum number value of a series of numbers, a plurality of sets of actuatable keys with the sets corresponding respectively to hundreds, tens and units digits, the keys of each set representing different digits between zero and nine, a source of voltage, a separate control relay for each of said keys, each of said control relays being energizable from said source in response to actuation of its key to operate a plurality of control switches, a first control switch of each control relay being effective when operated to maintain energization of its control relay when its actuated key is released to key in the represented digit, a second control switch of each control relay being effective when operated to prevent energization of control relays in response to subsequent actuation of keys in a set corresponding to digits smaller than a digit previously keyed in such set, a tens digit erasing relay energizable from said source in response to actuation of a hundreds key representing a hundreds digit larger than a previously keyed hundreds digit for operating a first erasing switch, said first erasing switch being effective when operated to deenergize the control relay corresponding to a previously keyed tens digit, a units digit erasing relay energizable from said source in response to actuation of a tens key representing a tens digit larger than a previously keyed tens digit for operating a second erasing switch, said second erasing switch being effective when operated to deenergize the control relay corresponding to a previously keyed units digit, separate third erasing switches operable in response to energization of each of said erasing relays, said third erasing switches being effective when operated to maintain energization of their erasing relays from said source through paths independent of paths which include keys and control relays, and a separate erasing control switch for each of said erasing relays, said erasing control switches being effective when opened subsequent to the keying of a digit in the associated set to deenergize their erasing relays for permitting the keying of a digit in the next following set.

45. In a device for determining the maximum number value of a series of numbers, a plurality of sets of actuatable keys with the sets corresponding respectively to hundreds, tens and units digits, the keys of each set representing different digits between zero and nine, a source of voltage, a separate control relay for each of said keys, each of said control relays being energizable from said source in response to actuation of its key, control means including first means operable in response to energization of a control relay to maintain energization of such control relay when its actuated key is released to key in the represented digit, said control means also including second means operable to prevent energization of control relays in response to subsequent actuation of keys in a set corresponding to digits smaller than a digit previously keyed in such set, erasing means energizable from said source in response to actuation of a key in a set representing a digit larger than a previously keyed digit in such set for deenergizing an energized control relay in the next following set, erasing control means operable in response to energization of said erasing means to maintain energization of said erasing means from said source through paths independent of paths which includes keys and control relays, and erasing control switch means effective when opened subsequent to the keying of a digit in a set to deenergize the erasing means for permitting the keying of a digit in the next following set.

7. In a device for determining the maximum number value of a series of numbers, a plurality of sets of actuatable keys with the sets corresponding respectively to hundreds, tens and units digits, the keys of each set rep-

resenting different digits between zero and nine, a source of voltage, a start switch, voltage applicator means for applying voltage from said source to said keys, said start switch being effective when closed to prepare said applicator means for energization from said source, said applicator means being energizable from said source through said closed start switch in response to actuation of a key in the hundreds key set for permitting the application of voltage to keys in the tens key set in response to actuation of a key in the tens set, a separate control relay for each of said keys, each of said control relays being energizable from said source in response to actuation of its key, control means including first means operable to maintain energization of a control relay when its actuated key is released to key in the represented digit, said control means also including second means operable to prevent energization of said applicator means and control relays in response to subsequent actuation of keys in a set corresponding to digits smaller than a digit previously keyed in such set, erasing means energizable from said source in response to actuation of a key in a set representing a digit larger than a previously keyed digit in such set for deenergizing an energized control relay in the next following set, erasing control means operable in response to energization of said erasing means to maintain energization of said erasing means from said source through paths independent of paths which includes keys and control relays, and erasing control switch means effective when opened subsequent to the keying of a digit in a set to deenergize the erasing means for permitting the keying of a digit in the next following set.

8. In a device for determining the maximum number value of a series of numbers, a plurality of sets of actuatable keys with the sets corresponding to different digit places of a number, the keys of each set representing different digits between zero and nine, a source of voltage, a start switch, voltage applicator means for applying voltage from said source to said keys, said start switch being effective when closed to prepare said applicator means for energization from said source, said applicator means being energizable from said source through said closed start switch in response to actuation of a key in the key set corresponding to the highest digit place for permitting the application of voltage to keys in the next following set in response to actuation of a key in the following set, a separate control relay for each of said keys, each of said control relays being energizable from

said source in response to actuation of its key, control means including first means operable to maintain energization of a control relay when its key is released to key in the represented digit, said control means also including second means operable to prevent energization of said applicator means and control relays in response to subsequent actuation of keys in a set corresponding to digits smaller than a digit previously keyed in such set, and erasing means energizable from said source in response to actuation of a key in a set representing a digit larger than a previously keyed digit in such set for deenergizing an energized control relay in the next following set.

9. In a device for determining the maximum number value of a series of numbers, a plurality of sets of actuatable keys with the sets corresponding respectively to hundreds, tens and units digits, the keys of each set representing different digits between zero and nine, a source of voltage, a separate control relay for each of said keys, each of said control relays being energizable from said source in response to actuation of its key to operate a plurality of control switches, a first control switch of each control relay being effective when operated to maintain energization of its control relay when its actuated key is released to key in the represented digit, a second control switch of each control relay being effective when operated to prevent energization of control relays in response to subsequent actuation of keys in a set corresponding to digits smaller than a digit previously keyed in such set, a tens digit erasing relay energizable from said source in response to actuation of a hundreds key representing a hundreds digit larger than a previously keyed hundreds digit for operating a first erasing switch, said first erasing switch being effective when operated to deenergize the control relay corresponding to a previously keyed tens digit, and a units digit erasing relay energizable from said source in response to actuation of a tens key representing a tens digit larger than a previously keyed tens digit for operating a second erasing switch, said second erasing switch being effective when operated to deenergize the control relay corresponding to a previously keyed units digit.
